INTERNAL COMBUSTION ENGINE

Simon Lake, Milford, Conn.

Application September 18, 1929, Serial No. 393,356
Renewed April 26, 1937

27 Claims. (Cl. 123—41)

This invention relates to internal combustion engines, and in its more specific aspects, to engines operating on the Diesel principle.

It has for its main objects: (1) To secure greater efficiency than has been heretofore obtained either in a two-cycle or four-cycle engine, both as to the quantity and cost of fuel and engine weight and space occupied per horsepower developed; (2) To obtain this greater efficiency and yet have a relatively slow-speed engine producing a substantially uniform torque; (3) To obtain greater reliability; (4) To facilitate easy regulation, adjustment and repair; and (5) To provide an engine of the type referred to which may be started automatically and which may be stopped and reversed as to direction of rotation at will.

These and other related objects are attained by this invention by the provision of means and combination of parts fully referred to in the annexed specification. Their attainment is very important and advantageous in connection with engines designed for motor vehicle and marine vessels, such, for instance, as submarines, but especially so in engines designed for aircraft, particularly heavier-than-air machines.

Another feature is the provision of opposed pistons in each cylinder so that in each cylinder each piston forms the head of the combustion chamber for the other piston, thereby saving the weight of the head which would otherwise be needed.

Other features and advantages will herein-after appear.

In the accompanying drawings, which illustrate one embodiment of this invention, that at present preferred—

Figure 1 is a longitudinal vertical section through the engine.

Fig. 2 is a transverse vertical section taken on the line 2—2 Fig. 1.

Fig. 3 is a similar view taken on the line 3—3 Fig. 1.

Fig. 4 is a similar view taken on the line 4—4 Fig. 1.

Fig. 5 is an end view of the engine looking from the right-hand side, as viewed in Fig. 1.

Fig. 6 is a detail view showing the pipe connection through which air is transferred from the crank case to the explosion chamber.

Fig. 7 is a detail view showing in transverse section a part of the engine through the center thereof and showing in detail the fuel and air mixing chamber and the valve controlling passage

of the mixture of fuel and air to the explosion chamber.

Fig. 8 is a plan view partly in section of the mechanism for starting and reversing the engine and the means for controlling and regulating the flow of fuel to the cylinders.

Fig. 9 is a detailed view of an automatically operated valve forming part of the reversing mechanism.

Fig. 10 is a detail view of a modified form of cam-operating mechanism to be used when the engine is to operate as a four cycle engine.

According to the present invention, the cylinders 10 of the engine are not arranged side-by-side in a vertical or horizontal plane as is customary, but, instead, are arranged squirrel-cage fashion in a frame work 11 having a base 12. In the cylinders 10 are pistons 13 each connected by a connecting rod 14 to a crank shaft 15. The crank shafts are disposed radially in the frame work 11 so that their axes all intersect the axis of a main drive shaft 16 to which power developed within the cylinders 10 is transmitted by means of bevelled gears 17 on the crank shafts 15 engaging a bevelled gear 18 on the main shaft 16.

In the form of the invention shown herein, the cylinders 10 are shown as mounted parallel with each other and with the main shaft 16, and this, for many reasons which will appear, is considered preferable at the present time. However, so far as some of the aspects of this invention are concerned, this precise arrangement is not necessary, and while still being arranged in a curved plane, the axes of the cylinders 10 may converge more or less toward each other and toward the main shaft 16, and this is particularly feasible with the bevelled gear drive 17—18 between the cranks 15 and main shaft 16, for it is merely necessary to have the teeth of the bevelled gears 17—18 at the proper angle.

As stated above, the engine of the present invention provides one cylinder 10 for each two pistons 13 and this is shown in Fig. 1, in which it will be noted that the cylinder comprises a straight cylindrical tube in which both pistons 13 may slide away from each other under the force of combustion occurring within a space or chamber 19 provided between them when they reach their closest proximity, as shown in the upper part of Fig. 1. The opposed pistons 13 have their crank shafts 15 located at opposite ends of the engine, and, accordingly, there is a bevelled gear 18 on the shaft 16 at each end of the engine.

The frame work 11 on which the cylinders 10

10, crank shafts 15, and main shaft 16 are mounted, comprises upright members 20 bolted to the base 12 and each having half bearings 21 for the crank shafts and full bearings 22 for the main shaft 16, in addition to tubular chamber portions or pockets 23 each forming one-half of the crank case for one of the cranks 15.

In addition to these two uprights 20, the casing comprises a pair of caps 24, one for each of the uprights 20. Each of the caps 24 has half bearings 25 for the crank shafts, and chambered portions 26 each forming one-half of the crank case for one of the cranks 15.

The caps 24 and the uprights 20 have external flanges 27 and 28 respectively, which are bolted together by bolts 29, see Figs. 2 and 8, after the crank shafts have been placed in proper position between the respective uprights 20 and their caps 24. By this operation, the bearings for the crank shafts 15 are completed and the two halves 23 and 26 of the crank case are brought together.

The uprights 20 and caps 24 are further fastened together by bolts 30 located in webs 31 and 32 in the uprights 20 and caps 24 respectively, at each side of the half bearings 21-25 which make up the bearings for the crank shaft 15, see Fig. 2.

30 The crank case chambers 23-26 in the uprights 20 and caps 24, respectively, are provided with transverse separating walls 33 which may extend radially so that each crank case is separate from each adjacent crank case.

35 In embodiments of this invention operating on a four-cycle principle, these separating walls 33 are not essential but are, however, shown herein since the engine illustrated is of the two-cycle type and precompression of air occurs in the crank case, as in other two cycle engines.

The cylinders 10, which as stated, are preferably plain cylindrical tubes, may be mounted in the frame work 11 in any suitable manner.

40 According to this invention, however, they are mounted so that they may be easily and individually removed from the engine for repair or replacement without dismantling the entire engine.

50 To so mount the cylinders 10, each upright 20 has secured to it by rivets 34 an annular member 35 having at equi-spaced points around its periphery half-round seats 36, see Fig. 3, into which the cylinders may be placed. Each of these half-round seats is provided with a half-round clamping member 37, which is secured in place by bolts 38 after the cylinders 10 have been placed in the half-round seats 36. Conversely, when it is necessary to remove a cylinder, the 55 clamping member 37 for that cylinder is removed and the cylinder, so far as its connection to the frame work 11 is concerned, is free to be lifted out. Other parts connected to the particular cylinder to be removed must, of course, be disconnected and further reference to this will be made below.

When the cylinders 10 are in place, their edges 39 are slightly free of the upright members 20 for the purpose of permitting longitudinal expansion of the cylinder, and are located adjacent circular holes 40 in the upright members 20 through which the connecting rods 14 extend. This places the interior of the cylinder between each piston 13 and its crank shaft 15 in communication with the crank case 23-26.

The frame work of the engine also comprises a tube 41 extending from one upright member 20 to the other and secured in place by rivets or bolts 42 passing through a flange 43 in the annular members 35. Among its other functions, which will be referred to below, the tube 41 serves to tie the upright members 20 together and, being tubular in form, serves to substantially strengthen and stiffen the frame work without itself adding very much weight to it.

10 Although many of the features of this invention are not limited to any particular kind or type of internal combustion engine, as herein illustrated, the engine is of the two-cycle type and operating on the Diesel principle, in which, as is well known, combustion of the fuel is produced by causing air trapped in the combustion chamber to be compressed to such an extent that the heat developed ignites the fuel when the latter is injected, and in which scavenging of the burnt gas resulting from the explosion and the injection of fresh air to the cylinder chamber is effected by compressing the air in the crank case on the power stroke of the pistons and allowing it, when the piston reaches the proper position in the cylinder at near the end of the power stroke, to rapidly surge into the cylinder, expell the burnt gases and remain in the cylinder to be compressed upon the return stroke of the piston.

Accordingly, the chambered portions 26 of each 30 cap 24 is provided with an air inlet 44 through which the atmospheric air may freely pass into the crank cases 23-26 and cylinders 10 below the pistons 13 during the inward or return movements of the pistons, that is to say, during the movement of the pistons from the position shown at the bottom of Fig. 1 to the position shown at the top of Fig. 1. The air inlets 44 are each controlled by a disc valve 45 so that so soon as its associated piston is driven downwardly, the valve 40 45 closes, causing the air trapped in the crank case to be compressed and to be held under compression until the piston 13 reaches the end of its power or outward stroke.

45 At this time, the air in the crank case is allowed to rapidly escape into the cylinder chamber through a port 46 therein, see Figs. 1 and 6, which is connected by a pipe 47 extending parallel with the cylinder and having at its opposite ends flanges 48 adapted to be fastened to the upright 50 members 20 which are provided with ports 49 each communicating with the crank case 23-26 at one end of the engine, see Figs. 2, 3 and 8. The pipe 47 is connected to the inlet port 46 of the cylinder by a coupling 50 held to the cylinder 55 10 by screws 51. The port 46 for each cylinder, as will be seen from Fig. 1, is so located that one of the pistons 13 on each cylinder acts as a valve to open and close it and does this at the end of the power stroke and beginning of the return 60 stroke of the piston respectively.

65 Each cylinder 10 is also provided with an exhaust port 52 through which the spent gases and the products of combustion may escape, and the exhaust port 52 is so located as to be opened and closed by one of the pistons at the end of the power stroke of the piston. Thus it will be seen that during the power stroke of the piston, air is compressed in the crank cases 23-26 and in the pipe 47 so that at the end of the power stroke 70 the inlet port 46 and outlet port 52 are opened and allow the spent gases to surge out of the port 52 and to be forced out by the compressed air rushing in through the port 46. It should be noted that each of the crank cases 23-26 associ- 75

ated with a particular one of the cylinders 10 is used to precompress the air instead of using only one crank case for this purpose as was the practice heretofore, and that, according to this invention, double the amount of compressed air is available for scavenging the cylinders.

It should also be noted that while both crank cases are used for precompressing the air for each cylinder, only one inlet port 46 and one outlet port 52 are provided and that these are located at opposite ends of the cylinder. Hence, at near the end of the power stroke, the air will rush through the cylinder in a substantially straight path from the inlet port 46 to the outlet port 52 and it will not be necessary to double back upon itself or otherwise follow a tortuous path as it would do in case any other arrangements were made.

The merge surge of compressed air from the crank cases 23-26 through the cylinder at the end of the power stroke to blow out the products of combustion is not depended upon solely, according to this invention for scavenging the cylinders. Instead, there is provided a suction device for assisting in this operation.

For this purpose, the exhaust ports 52 are connected to ports 53 leading to the interior of the drum or tube 41 directly behind a division wall 54 in the tube and in the compartment 55 of the tube 41 thus formed, there is provided one or more sets of fan blades 56 mounted on a sleeve 57 supported on the power shaft 16 by means of ball bearings 58, see Fig. 1, and driven by means described below. The direction of the pitch and rotation of the blades 56 is such as to tend to produce a partial vacuum in the chamber 55 forcing the air from the compartment 55 through exhaust pipes 59 leading to an exhaust manifold 60 connected to an escape pipe 61.

The exhaust pipes 59 are placed around the tube 41 and pass through the rear upright 20 and cap 24 in the spaces between the bearings 21-25 for the crank shafts, as shown in Fig. 4, while the manifold 60 to which the exhaust pipes 59 are connected lies in an annular chamber 62 provided in the cap 24 at the right-hand side of the engine, as viewed in Fig. 1.

To insure that the gases, both air and the products of combustion, in the compartment 55 are forced out into the exhaust pipe 59 rather than being merely caused to circulate within the compartment, a centrifugal fan 63 is provided on the sleeve 57 in the plane of the openings of the exhaust pipes as shown in Figs. 1 and 4, so that the spirally arranged blades 64 of the centrifugal fan 63 force the air and spent gases outwardly into the exhaust pipes 59 as the air and other gases are forced between the fan blades 64 by the blades 56.

Thus it will be seen that due to the rotation of the fan blades 56 and 64, as soon as an exhaust port 52 is opened in one of the cylinders, the gases therein are forced out of the cylinder by the in-rushing precompressed air from the crank case and further are sucked out by the action of the blades 56 and 63 very rapidly and completely, the exhaust gases being quickly carried off and expelled through the escape pipe 61 and allowing a flow of fresh air into and through the cylinder before the inlet port 46 is again closed upon the return stroke of the piston.

In the operation of scavenging a cylinder of spent gases and filling a cylinder with fresh air preparatory to the compression stroke, not only the air which was precompressed in the crank

cases by the power stroke of the pistons is employed, but, due to the provision of the suction fans 56 and 63, it is intended that other air at atmospheric pressure be taken into the cylinder. This additional air is taken in through the inlet ports 46 in the covers 24 and is allowed to enter by reason of the disc valve 45 which opens automatically as soon as the pressure within the cylinder and crank cases becomes less than atmospheric pressure after expansion of the pre-compressed air and due to the suction or partial vacuum created by the fan blades 56 and 64. Of course, these disc valves 45 immediately close as soon as the air in the crank cases begins to be compressed on the power strokes of the pistons.

When the engine is of the air-cooled type as shown herein, it is preferable that fans or other air-impelling means be employed for assisting in cooling the cylinders particularly the inwardly located external walls thereof. To accomplish this, the present invention provides fan blades 65 on the fan-sleeve 57 which it will be remembered is the sleeve which carries the fan blades 56 and 63. These fan blades 65 are located in the tube 41 in advance of the dividing wall 54 which forms a compartment 66 between the wall 54 and the front upright 20.

Fresh air is drawn into the compartment 66 by the fan blades 65 through an annular chamber 67 in the front or left-hand cap 24 of the frame and passes through openings 68 between the bearings 21-25 into an annular chamber 69 in said upright 20 which has openings 70 leading into the chamber 66. The air impelled by the fan-blade 65 passes out of the chamber 66 through ports 71 in the direction of the arrows shown in Fig. 1 and impinges against the walls of the cylinders and cools them, the cylinders being preferably provided with fins 72 to further increase radiation and facilitate cooling.

The means for driving the sleeve 57, which carries the cooling blades 65 and exhaust blades 56 and 63, comprises a gear 73 secured to the sleeve and meshing with a gear 74 mounted on a stud shaft 75 carried by a bracket 76 secured to the tube 41, the gear 74 being driven by the power shaft 16, as will be described below.

Since the engine herein illustrated is reversible, that is to say, since the pistons are capable of driving the power shaft 16 in either direction, means are provided by this invention for enabling the sleeve 57 carrying the fan-blades to rotate in one direction only, regardless of the direction of rotation of the power shaft.

For this purpose, reversible gearing is provided between the power shaft 16 and the gear 74 which drives the fan-sleeve. This reversible gearing comprises an external gear 77 and an internal gear 78 both secured on the power shaft 16. Either of these two gears is adapted to mesh with a pinion 79 slidably mounted on a sleeve 80 carried by the gear 74 and the pinion 79 is adapted to be shifted by a forked arm 81 pivoted at 82 on the upright member 20. By moving the forked arm 81, the pinion 79 may be moved out of mesh with the external gear 77 into mesh with the internal gear 78 or vice versa. The shifting fork is normally urged to the position shown in Fig. 1, by a spring 83 located between it and the frame. When the engine is operating forwardly, the spring 83 keeps the pinion 79 in mesh with the gear 77 on the power shaft and this causes the fan-blades to rotate in the proper direction. When, however, the engine is re-

versed, the forked arm 81 is rocked, by means hereinafter described, to move the pinion 79 into mesh with the internal gear 78, and thus causes the pinion and fan-blades to be driven in the same direction as before, even though the shaft is rotating in the opposite direction.

As far as some of the aspects of this invention are concerned, particularly a number of those described above, the engine as illustrated herein may operate upon relatively highly volatile and inflammable fuel as, for instance, gasoline or heavier and less inflammable oil, such as is known as Diesel engine oil. In either event, each cylinder is provided with an inlet port 84 communicating with the chamber 19 between the heads of the opposing pistons 13. In the former case, the fuel may be carbureted and fed into the chamber 19; and ignition means, such as spark plugs, may be supplied for each cylinder to cause combustion of the fuel.

The engine, as illustrated herein, however, is of the Diesel type, which, as is well known, employs no carburetor and depends upon the heat resulting from the compression of the air in the chamber 19 on the return stroke of the pistons to explode or burn the combustible material injected into the cylinder.

Accordingly, the engine of the present invention is provided with a fuel oil supply pipe 85 which has a branch 86 provided for each cylinder leading into a regulating mechanism 87 also provided for each cylinder. Each regulator or injector 87 comprises a block 88, see Fig. 8, secured to the cylinder, as, for instance, by screws 89, and has a chamber 90 into which the oil may flow from the branch pipe 86. Communicating with the chamber 90 is a duct 91, passage of the oil to which is controlled by a valve 92 slidably mounted in the chamber 90. The duct 91 leads into a charge regulating chamber 93 in which is mounted an ejector plunger 94 on a rod 95, which plunger is normally urged toward the left, as viewed in Fig. 8, by a spring 96, located between a collar on the rod and the side of the clamping member 37 in a hole in which the rod 95 is guided for sliding movement.

From the charge regulating chamber 93 the fuel oil may flow, when permitted so to do by a valve 98, to a duct 99 leading to a mixing chamber 100, see Fig. 7, from which it may pass through a helically fluted regulating screw 101 and nozzle 102 to the combustion chamber 19. The screw 101 has suitable packing means 103 and an accessible finger-piece or nut 104 by means of which it may be adjusted up or down to bring a conical tip 105 on the screw farther from or closer to a conical apertured seat 106 of the nozzle 102. This is done to regulate the flow of fuel from the nozzle to adjust it for fuel oil of different qualities, particularly with reference to the viscosity of the oil; also to clean the nozzle of any foreign matter which might lodge therein.

The valve 92 is provided with an operating stem 107, while the valve 98 is provided with an operating stem 108, and these stems extend over toward and are operated by the left-hand or forward crank shaft of the cylinder to which the regulator and injector 87 is connected, the valve stems 107 and 108 being slidably mounted in the clamping member 37 adjacent the front of the upright 20.

For operating the stems 107 and 108 by the crank shaft, the latter is provided with a cam 109 moving in the path of a rocker arm 110 pivotally mounted on a stud 111 carried by a ring

112 mounted on the annular portion of the upright 20.

Assuming the parts to be in the positions shown in Fig. 8, the cam 109 in rotating engages a roller 113 on the rocker 110 and causes the latter to be rocked in counterclockwise direction. This causes a roller 114 on the rocker to engage a tappet 115 slidably mounted on a table 116, formed integral with the half-clamp 37 which holds the cylinder in place on the upright 20, by means of rollers on screws 117 which ride in a slot 118 in the tappet. The tappet 115 has a broad head 119 located in position to engage the ends of the valve stems 107 and 108 when the rocker arm moves the tappet toward the center 15 of the engine.

The stem 107 being longer than the stem 108 is the first one to be engaged by the head 119 of the tappet. This causes the valve 92 to be moved to the right, as viewed in Fig. 8, to close-off the duct 91 and prevent return flow of fuel contained in the charge regulating chamber 93. After this is done, the head 119 of the tappet engages the valve stem 108 and moves the valve 98 from its seat, permitting the fuel to flow 25 through the duct 99 to the chamber 100 and from thence through the nozzle 102 to the combustion chamber.

At this time, the fuel is ejected from the chamber 93 by the plunger 94 under the action of 30 spring 96. In the operation of the engine, the motivating power for this purpose was previously stored in the spring 96 by the pressure on the fuel oil in the branch 86, chamber 90 and chamber 93, when the latter was allowed to be in 35 communication with the chamber 90 through the duct 91 being opened by the valve 92, while the valve 98 was closed, the oil under pressure forcing the plunger 94 toward the right, as viewed in Fig. 8.

Thus, it will be seen that as soon as the duct 91 is closed and the valve 98 is opened, the spring 96 may force the fuel past the valve 98 and eject the fuel oil therefrom and force it into the mixing chamber 100 and ultimately into the 45 cylinder 10.

The quantity of fuel oil injected into the cylinder at each operation is controllable, according to this invention, so that the speed and power developed by the engine may be varied as desired. 50 This is accomplished in a very simple and advantageous manner in the form of the invention illustrated herein, by regulating the range of movement of the ejector plunger 94.

To do this, the plunger rod 95 at its end which 55 protrudes through the member 37 toward the right-hand or rear upright 20 is provided with a stop collar 120 fixed thereon, and located in its path is a stop 121 which limits the ejecting movement of the plunger and therefore regulates 60 the quantity of fuel oil ejected by the plunger 94 at each operation thereof.

There is a stop 121 for each cylinder and these are mounted on a ring 122 which is supported on the right-hand upright 20 for rotation and is 65 adjustably rotated by means of a segmental rack 123 meshing with a pinion 124 secured to a shaft 125 connected to a control lever not shown.

The operating edge of each stop 121 is sloped from one end where it lies close to the ring 122 70 to the other end where it is spaced substantially therefrom. Thus, when the ring is rotated the operating edges 126 are moved closer to or farther from similarly inclined operating edges 127 of the stop collars 120, and thus permits less or 75

greater ejecting movement of the plungers 94 under the influence of their spring 96, according to the setting of the ring 122.

Although it is not essential to the successful operation of the engine, it is preferable in large size engines or where heavy oil is used, that air under compression be caused to flow into the jet 102 so as to atomize the oil being ejected through the jet. This is accomplished in the form of the invention shown herein, by providing a pipe 128 connected to a reservoir of compressed air, with a branch 129 for each cylinder. The branch 129 leads into a chamber 130 in the regulator mechanism 81 and this chamber has a duct 131 leading into another chamber 132 having a valve 133 on a valve stem 134, which like the valve stems 107 and 108 extends through, and is guided by member 37 and the front and left-hand upright 20, to be operated by the head 119 of the tappet 115. The valve 133 is opened by operation of the cam 109, the rocker 110, and the tappet 115 simultaneously with the opening of the fuel-oil valve 92. As the fuel oil passes through the chamber 100, air under pressure in the chamber 132 passes the valve 133 and enters a duct 135, then passes into said chamber 100 and mixes with the fuel oil in said chamber and then passes through the helical groove in the regulating screw and is there further broken up before it enters the cylinder 10, being broken up into fine particles so as to form a mist which will freely ignite and burn when it contacts with the air in the chamber 19 which was brought to high temperature, due to the compression resulting from the approaching movement of the opposed pistons 13. The pressure on the auxiliary air fed to the cylinders by the compressed air line 128 is, of course, greater than the pressure of the air under compression in the cylinder at the time it and the fuel oil is being fed into the cylinder.

The engine of this invention is started and brought up to sufficient speed, so that the air in some of the cylinders will be compressed rapidly enough to cause it to ignite the fuel, by compressed air supplied to the cylinders by the compressed air line 128, above described. For this purpose, means are provided for introducing relatively large quantities of compressed air to the cylinders of the engine, which at the time of starting have their pistons located at the proper point to receive the air.

For the purpose of controlling the introduction of compressed air to those cylinders whose pistons are in the proper position to receive it, the crank shaft 15 for each right-hand piston, as viewed in Figs. 1 and 8, is provided with a cam 137 which co-operates with a rocker arm 138 having rollers 139 and 140 to engage and be engaged by the cam 137, and other rollers 141 and 142 adapted to engage the head 143 of a tappet 144 held for sliding movement on a table 145 formed integral with a half clamp 37 for the right-hand end of the cylinder by means of rollers or screws 146 which ride in a slot 147 in the tappet 144. The head 143 of the tappet 144 is adapted, when operated, to engage an operating stem 148 for the valve mechanism which permits compressed air from the chamber 131 to flow to the cylinder.

This valve mechanism comprises a valve 149 on a valve stem 150, and is adapted to normally close a passage 151 leading to a duct 152 in communication with a circular chamber 100 which

opens into the cylinder and in which the jet 102 is located.

To permit the valve 149, which is of substantial size so as to allow a large quantity of compressed air to quickly pass into the cylinder, to open, it is provided with a pilot valve 153 on a stem 154 slidably mounted within the stem 150 and closing an opening 155 through the valve 149, the valve stem 150 having openings 156 through which air may pass to the duct 152, and into the chamber and thus raise the pressure on the backside of the valve 149 preparatory to its opening.

The pilot valve 153 has a spring 157 normally tending to keep it closed, and at its other end has a pin 158 engaging the end wall 159 of a hollowed end 160 on the operating stem 148, in which the pilot valve stem 154 and the main valve stem 150 extends. Normally, the end 161 of the main valve clears the wall 159 so that the first movement of the operating stem 148, by engaging the pin 158, opens the pilot valve 153 and then the subsequent movement of the operating stem 148 causes the end 161 of the main valve stem 150 to be engaged by the wall 159 to open the main valve 149.

The rocker arms 138 are mounted for oscillation on a starting ring 162 rotatably mounted on the right-hand upright 20. The starting ring 162 is provided with a segmental rack 163 adapted to mesh with a pinion 164 on a control shaft 165 so that rotation of the shaft by a control wheel, or lever, not shown, may cause the starting ring 162 to be adjusted to desired position.

When the engine is running, the starting ring 162 is in a midway position so that neither of the rollers 139 or 140 are in range of the cam 137, and thus while the engine is running, the rockers 138 do not operate, nor does the valve 149 or its pilot valve 153 open.

When, however, the engine is stopped and it is desired to start it, the operator rotates the shaft 165 to shift the ring 162 in either direction, depending upon whether it is desired that the engine run forwardly or backwardly, that is to say, in one direction or the other.

Assuming that it is desired to have the engine rotate forwardly, with the parts in the position shown in Fig. 8, the ring 162 is moved upwardly, as viewed, to bring the rollers 140 into engagement with those cams 137 which happen to be in position to be engaged. That is to say, with those cams whose pistons are just beginning what would be their power stroke when the engine is running forwardly, i. e. in the direction of the arrow shown on the cam 137. For instance, as shown in Fig. 8, the piston controlled by the cam 137 is well along in its power stroke, and when the ring 162 is shifted, the roller 140 engages the land of the cam 137 and causes the rocker 138 to oscillate and open the pilot valve 153 and main valve 149 for allowing compressed air to enter the cylinder with which the cam 137 is associated.

This will cause the engine to start to turn over, whereupon due to the mutual movement of the rotation of the other cams 137 and the advancement of the ring 162, the rollers 140 belonging to successive cylinders will be engaged by the cams 137 to admit compressed air to the cylinders controlled thereby, until the ring 162 reaches the limit of its movement and then the rotation of the crank 15, due to the operation of the engine by compressed air, will cause the valves 153 and 149 of the cylinders to be opened successively and

allow the compressed air to surge into the chambers 19 and drive the pistons 13 apart. This operation of the engine by compressed air is maintained until the engine reaches sufficient speed so that fuel injected into the chambers 19 of some of the cylinders will be ignited by the heat generated by compressing the air therein.

Before starting the engine, the fuel control ring 112 is shifted to a neutral position so that 10 the cam 109 of the left-hand crank shaft will not engage and operate the rocker 110, and thus during the initial starting movement, no fuel is injected in the cylinder.

After the engine is started by rotation of the 15 ring 162, and while being brought up to speed, the operator shifts the control ring 112 through operation of the shaft 167 which has a pinion 168 meshing with a rack 169 on the ring 112 so that the rollers 113 on the rockers 110 are brought 20 into range of the cams 109. This causes fuel to be injected into the cylinder at the proper time, and fuel ignites and burns and the engine begins to operate under force of the combustion of the fuel oil.

25 The expansion of the compressed starting air in the cylinders tends to cool the walls of the cylinders and this tends to retard the starting of proper combustion of the fuel oil. Consequently, according to this invention, after the 30 inertia of the parts is overcome and the engine speeds up, compressed starting air is withheld for some of the cylinders to give them an opportunity to generate sufficient heat by compressing therein air taken in through their crank cases so 35 as to cause combustion to take place. Accordingly, when sufficient speed is obtained, the fuel control ring is moved to bring the rollers 113 on the rockers 110 into range of the cam 109 so that fuel and auxiliary air is fed to the cylinders. At the same time the starting ring is retarded slightly, i. e. moved to neutral position, so 40 that rollers 140 belonging to certain of the cylinders will be out of range of their cams 137a which for this purpose are shorter than the cams 45 137 on the others of the cylinders, whereby the starting air valves 149 and 153 for these cylinders will not open to admit compressed air. This allows the air in these cylinders to ignite the fuel when sufficient speed has been obtained.

50 When the cylinders with short cams 137a begin to fire in regular order, the ring 162 is completely returned to neutral position by rotation of the control shaft 165 so that the cams 137 will no longer reach the rollers 140 to oscillate 55 the rockers 138.

50 To stop the engine, the operator rotates the shaft 167 so as to move the rockers 110 out of range of the cams 109 and thus cut off the supply of fuel and auxiliary air to the cylinders.

60 To cause the engine to travel in reverse direction from stopped position, the shaft 165 is rotated so as to cause the ring 162 to be shifted downwardly, as viewed in Fig. 8. This will move the rollers 139 on the rockers into engagement 65 with those cams 137 and 137a of the cylinders whose pistons are traveling in what is the return or compression stroke when the engine is being operated in a forward direction. The cranks of these pistons having not yet crossed the dead 70 center line between the wrist pins of the pistons and the cranks, air admitted to these cylinders and impinging against these pistons causes the pistons to be driven apart, and thus causes the direction of motion of the engine to be the reverse of that previously described.

The co-action of the rollers 139 and the cams 137 and 137a is the same as between the rollers 140 and the cams 137 as that above described, except for timing, as just stated.

As above stated, the rollers 113 and 114 on the 5 rocker 110 operate to control the opening of the fuel valve 92 and auxiliary air valve 133 when the engine is going forwardly. These same functions are performed by rollers 170 and 171, also carried by the rocker 110, when the engine is operating in 10 reverse direction. Being on the opposite side of the stud shaft 111 from the rollers 113 and 114, the rollers 170 and 171 oscillate the rocker in reverse direction but of course this is of no consequence since the tappet 115 moves in the same 15 way whether it is operated by the roller 114 or the roller 171.

The point in the operation of the pistons at which fuel is injected may be controlled during the running of the engine by adjusting the control ring 112 so that the injection of the fuel oil may be advanced or retarded to obtain best efficiency. This is done by adjusting the control ring 112 more or less, either toward or from its neutral position so that the rollers 113 or 170, 25 according to the direction in which the engine is being operated, may be engaged later or sooner in the rotation of the crank shaft, and the arrangement may be such that the point of injection of the fuel, and consequently the ignition or 30 combustion point, may be advanced so that the engine fires just before the pistons complete the ends of their compression strokes.

Thus, it will be seen that the engine may be controlled or throttled to vary the amount of fuel 35 injected, by adjusting the ring 122, and may be controlled as to timing, i. e. the point in the cycle of operations where fuel is injected by adjustment of the ring 112.

As described above, the fan blades 56 and 65 40 are always driven forwardly whether the engine is operating forwardly or in reverse, and this is controlled by the forked arm 81 normally held by the spring 83 in position to cause the fans to operate forwardly when the engine rotates forwardly. However, when the engine is operated in reverse direction, a piston 172 sliding in a cylinder 173 and connected by a link 174 to the forked arm 81, causes the arm to be shifted so as to move the pinion 79 into engagement with the internal gear 78, against the tension of the 50 spring 83.

The piston 172 is operated by compressed air and is connected by a pipe 175 leading to a three-way valve 176. This valve has a pipe 177 leading to the compressed air pipe 128 above mentioned, and a cylindrical vane 178 having an operating arm 179, see Figs. 8 and 9. The operating arm 179 is normally held in the position shown in Figs. 8 and 9 by a spring 180 so that a passage 60 181 in the vane normally connects the pipe 175 leading to the cylinder and piston 173, 172 with an escape orifice 182 in the valve. When the operating arm 179 is rocked, however, the communicating passage 181 moves beyond the outlet 65 orifice 182 so that the cylindrical vane closes the same and continues to move until the pipe 177 from the compressed air pipe is placed in communication with the pipe 175 to the gear shifting cylinder and piston 173, 172 so that the compressed air will operate the piston to shift the 70 pinion 79 into mesh with the internal gear 78.

The operating arm 179 of the automatic valve 176 is adapted to be operated by a cam 183 on the control ring 112, and this cam is so positioned 75

that when the control ring is shifted from neutral position toward reverse driving position, that is downwardly, as viewed in Fig. 8, the cam 183 engages the arm 179 to shift the valve.

5 It will, of course, be understood that while the engine as herein illustrated comprises eight cylinders each having two opposed pistons, any number of pistons may be employed within the scope of this invention, and if desired, an even greater 10 number of cylinders could be employed without materially increasing the space occupied by the engine by placing the cylinders a little closer together; or the engine may be made larger and a larger number of cylinders employed. Or, 15 when the engine is to be used for motor vehicles, some of the cylinders, for instance the lower three in Fig. 3 may be omitted entirely, in which case the pistons of the remaining cylinders will be so connected by their crankshaft 15 to the 20 main driving gears 18 as to split the firing points of the cycle equally between them.

This, as well as the varying of the firing order, if desired, may be accomplished by simply placing the cylinders in the desired relative positions 25 before the bevelled driving gears 18 are secured in place on the power shaft 16.

By this manipulation of the pistons in the cylinders, they may be made to fire in any way desired. That is to say, the firing order of the cylinders may be in regular succession or alternately as cylinders 1, 3, 5, 7, 2, 4, 6, 8, or in fact in any way desired. Of course, these variations and changes may be effected without requiring any 30 separate alternation or adjustment of mechanism, for the relations between the cams 109 which are individual to each cylinder and their co-operating rollers 113 and 170 are properly and automatically varied by simply manipulating the pistons.

40 Sometimes it is desired to have the outlet port 52 of the cylinder opened a little ahead the air intake port 46. This can be accomplished, according to the present invention, by adjusting the right-hand set of pistons 13 slightly in advance in their cycle with relation to the left-hand pistons, before the right-hand bevelled gear is secured in place, and thus a lead is obtained to give the 45 exhaust gases a chance to expand and start out from the cylinder before the air intake port 46 is opened.

It should be noted that by having the cams 109 for controlling fuel injection individually to each cylinder, not only is it possible to adjust the pistons as of the respective cylinders relative 55 to each other but that the back lash which would result from reversing the direction of travel in any system of gear is avoided, and thus, according to the present invention, the timing of the fuel injections, and consequently combustion, is 60 always accurate and uniformly determined whether the engine is rotating forwardly or the reverse.

The compressor, not shown, for producing the compressed air, which is fed from the reservoir, 65 not shown, through the line 128 to the several regulating and injecting mechanisms 87 may be driven by a sprocket 184 carried by the power shaft 16 and connected to the shaft by a clutch 185.

70 Variations and modifications may be made within the scope of this invention and portions of the improvements may be made without others.

For instance, when it is desired to have the engine operate on a four cycle principle, it is 75 necessary to change the operation of the cam 109

and the cam 131 so that they will make but one revolution for two revolutions of the crank shaft. One way of accomplishing this is shown in Fig. 10, wherein the crank shaft 15 has secured to it a pinion 186 meshing with an internal gear 187 on a cam 188 mounted on a stud shaft 189. The ratio between the pinion 186 and the internal gear 187 is such that for each revolution of the crank shaft the cam 188 makes only one-half a revolution, that is to say, the cam only makes one 10 revolution for each two of the crank shafts.

Having thus described the invention, what is claimed as new and for which it is desired to obtain Letters Patent, is:

1. In a multi-cylinder Diesel-type engine, a fuel 15 injector for each cylinder including a chamber; a valve for closing said chamber; mechanism for automatically opening and closing said valve; means for maintaining fuel in said chamber under pressure and injecting the fuel into the cylinder when said valve is opened, said means including a plunger and a stop device on the plunger for determining its length of stroke in injecting direction; and means common to all of said injectors and comprising cooperating stops. 25

2. In a multi-cylinder Diesel-type engine, a fuel injector for each cylinder including a chamber; a valve for closing said chamber; mechanism for automatically opening and closing said valve; means for maintaining fuel in said chamber under pressure and injecting the fuel into the cylinder when said valve is opened, said means including a plunger and a stop device on the plunger for determining its length of stroke in injecting direction; and means common to all of said injectors and comprising cooperating stops, said last-named means being adjustable to increase or decrease the length of strokes of the plunger. 35

3. In a multi-cylinder Diesel-type engine, having pistons, a crank shaft for each piston, means for starting the engine by compressed air including a plurality of valves one individual to each cylinder for introducing compressed air to the cylinder, a tappet for the valve, a rocker for operating the tappet, and a cam on a crank shaft associated with each cylinder for operating said rocker so that compressed air is introduced into a plurality of the cylinders simultaneously according to the position at the moment of the individual crank shafts and cams carried thereby and rockers engaged by the cams. 40

4. In a multi-cylinder Diesel-type engine having pistons, a crank shaft for each piston, means for starting the engine by compressed air including a plurality of valves one individual to each cylinder for introducing compressed air to the cylinder, a tappet for the valve, a rocker for operating the tappet, a cam on a crank shaft associated with each cylinder for operating said rocker, and means common to all of said rockers 45 for supporting them for movement into and out of range of said cams, said rockers each having two cam followers, one to engage and to be engaged by the cams when the engine is started forwardly and the other when the engine is started in reverse direction so that compressed air is introduced into a certain plurality of cylinders simultaneously according to the position at the moment of the individual crank shafts and cams carried thereby and rockers engaged by the 50 cams, and according to the direction in which it is desired to have the engine run. 55

5. In a multi-cylinder Diesel-type engine having pistons, an individual crank for each piston, means for starting the engine by compressed air 60

- including a plurality of valves one individual to each cylinder for introducing compressed air to the cylinder, a tappet for the valve, a rocker for operating the tappet, a cam on a crank shaft associated with each cylinder for operating said rocker, means common to all of said rockers for supporting them for movement into and out of range of said cams so that compressed air is introduced into a plurality of the cylinders simultaneously according to the position at the moment of the individual crank shafts and cams carried thereby and rockers engaged by the cams, some of said cams being shorter than others, and said means for supporting the rockers being movable to a position where the rockers are engaged by the long cams and not engaged by the short cams whereby compressed air is admitted to only cylinders whose cams are long, and means for injecting fuel for a regular firing charge into those cylinders in which compressed air has not been admitted.
6. In a multi-cylinder Diesel-type engine, a fuel injector for each cylinder including a chamber; a valve in said chamber; a plunger in said chamber; a spring on said plunger; mechanism for filling said chamber with fuel oil, while the valve therein is closed, with sufficient pressure to move the plunger to a back position and at the same time storing energy in the spring associated therewith; means for opening the valve, whereupon the spring alone, due to the energy stored therein, urges the plunger back into the chamber to force fuel oil into the cylinder; and means common to all of said fuel injectors for regulating the spring urged travel of the plunger into the chamber and thereby regulating the displacement and quantity of fuel injected at each operation of the injector.
7. An internal combustion engine having a plurality of cylinders and pistons, each cylinder containing a pair of pistons; a crank shaft for each piston; means for starting the engine by the application of compressed air to the cylinder, said means including a valve individual to each cylinder; and a plurality of cams, one for each cylinder, to operate the valve and admit compressed air to the cylinder, each cam being mounted on a crank shaft operated by one of the pair of pistons in the cylinder.
8. In a multi-cylinder Diesel-type engine, a fuel injector for each cylinder including a chamber; a reciprocating plunger in said chamber, and a spring to impart working travel to the plunger; means common to all of said fuel injectors for controlling the extent of spring actuated reciprocatory movement of the plunger in working direction to regulate the quantity of fuel injected at each operation of the injector; and means individual to each cylinder and including a valve controlling the passage of the fuel from said chamber to said cylinder for determining the point in the cycle of operation of each cylinder at which said injector operates.
9. In a multi-cylinder Diesel-type engine, a fuel injector for each cylinder including a chamber, a reciprocating plunger in said chamber, and a spring to impart working travel to the plunger; manually controllable means common to all of said fuel injectors for controlling the extent of spring actuated reciprocatory movement of the plunger in working direction to regulate the quantity of fuel injected at each operation of the injector; means individual to each cylinder and including a valve controlling the passage between the cylinder and the chamber for determining the point in the cycle of operation of the cylinder at which said injector operates; and manually controllable means for adjusting the last-named means of all of the cylinders at one time.
10. An internal combustion engine having a plurality of cylinders and pistons; individual crank shafts for each piston; means for controlling the point of fuel-injection into the cylinders including a plurality of cams, each cam individual to a crank shaft; rockers, one engaged by each of said cams; and means for simultaneously and uniformly varying the relation between each of said rockers and its associated cam.
11. An internal combustion engine having a plurality of cylinders and pistons; a crank shaft for each piston; a main shaft; a gear drive between said crank shafts and said main shaft; fuel injecting means individual to each cylinder; means for controlling the point in the cycle of operations of the piston in which fuel is injected by said injecting means and including a cam on a crank shaft associated with each cylinder; rockers engaged by each of said cams; and means for simultaneously and uniformly varying the relation between each of said rockers and its associated cam to simultaneously and uniformly vary the points in the cycle of operations of the pistons in which fuel is injected.
12. In a multi-cylinder Diesel-type engine, a plurality of cylinders each having a crank shaft individual thereto; a fuel injector for each cylinder including a reciprocating plunger and a spring to impart working travel to the plunger; means common to all of said fuel injectors for controlling the extent of spring actuated reciprocatory movement of the plungers in working direction; means actuated by each crank shaft individually at a point in the cycle of operation of each cylinder for operating the injector; and means for supporting said last-named means for simultaneous bodily movement to uniformly vary the points in the cycle of operations at which the injectors operate.
13. In a multi-cylinder Diesel-type engine, a plurality of cylinders each having a crank shaft individual thereto; a fuel injector for each cylinder including a reciprocating plunger and a spring to impart working travel to the plunger; means common to all of said fuel injectors for controlling the extent of spring actuated reciprocatory movement of the plungers in working direction; means actuated by said crank shafts individually at a point in the cycle of operation of each cylinder for operating said injector; and manually adjustable means for shifting the last-named means to uniformly vary the points in the cycle of operations at which the injector operates.
14. In a multi-cylinder Diesel-type engine, a plurality of cylinders each having a crank shaft individual thereto, one fuel injector for each cylinder; means actuated by the crank shafts individually at a point in the cycle of operation of each cylinder for operating the injector; means for supporting said last-named means for simultaneous bodily movement to vary the points in the cycle of operations at which the injectors operate; and means for shifting said last-named means from neutral position in one direction to one range of operating positions for one direction of operation of the engine and in another direction to another range of operating positions for the reverse direction of operation of the engine.
15. In a multi-cylinder Diesel-type engine, a

plurality of cylinders each having a crank shaft individual thereto; one fuel injector for each cylinder; means actuated by the crank shafts individually at a point in the cycle of operation 5 of each cylinder for operating the injector; means for supporting said last-named means for simultaneous bodily movement to vary the points in the cycle of operations at which the injectors operate; and means for shifting said last-named 10 means from neutral position in one direction to one range of operating positions for one direction of operation of the engine and in another direction to another range of operating positions for the reverse direction of operation of the engine, said last-named means being variable to 15 advance or retard the points in the cycles of operations of the cylinder in which said injectors operate.

16. In a multi-cylinder Diesel-type engine, a 20 plurality of cylinders each having a crank shaft individual thereto; one fuel injector for each cylinder; means actuated by the crank shafts individually at a point in the cycle of operation of each cylinder for operating the injector; means 25 for supporting said last-named means for simultaneous bodily movement to vary the points in the cycle of operations at which the injectors operate; and means for shifting said last-named means from neutral position in one direction to 30 one range of operating positions for one direction of operation of the engine and in another direction to another range of operating positions for the reverse direction of operation of the engine, and the position of said means in either 35 forward or reverse position being variable to advance or retard the points in the cycles of operations of the cylinders in which said injectors operate.

17. In a Diesel-type engine having a plurality 40 of cylinders and pistons, a crank shaft for each piston, a fuel injector for each cylinder comprising an operating part, a cam on the crank shaft associated with each cylinder, a plurality of interponents, one between each of said cams and its 45 associated injector and individual thereto, and manually operated means for shifting said interponents simultaneously relative to the cams and the injectors.

18. In a Diesel-type engine having a plurality 50 of cylinders and pistons arranged in squirrel-cage form, a crank shaft for each piston, a fuel injector for each cylinder comprising a valve, a tappet for operating the valve, a cam on the crank shaft, a rocker between the cam and the 55 tappet adapted to be operated by the cam and to operate the tappet, and a ring extending around the cylinders on which said rockers are mounted, said ring being rotatably adjustably mounted for shifting the position of the rockers relative to 60 the cams.

19. In a multi-cylinder Diesel-type engine having a plurality of cylinders arranged squirrel-cage fashion, a piston in each cylinder, an individual crank shaft for each piston, means for 65 starting the engine by compressed air including a plurality of valves, one individual to each cylinder for introducing compressed air to the cylinder, a tappet for each valve, a rocker for each valve cooperating with the tappet, a cam on the 70 crank shaft associated with each cylinder for operating said rocker, and a ring extending around said cylinders and supporting the rockers, said ring being mounted for rotating movement to move the rockers into and out of range of the 75 cams.

20. The invention as defined in claim 5, in which the rockers each have two cam followers, one to engage and be engaged by the cam when the engine is started forwardly and the other to engage and be engaged by the cam when the 5 engine is started in reverse direction.

21. In a Diesel-type engine having a plurality of cylinders, pistons, and means driven by the pistons, means for starting the engine by compressed air including a plurality of valves each 10 individual to one cylinder, a tappet for each valve, a rocker for operating each tappet and individual to each valve, a plurality of cams each individual to one of the cylinders and controlled as to position by the position of the piston 15 in its associated cylinder, and settable means for making said cams operable on said rockers and tappet to open a plurality of said valves to admit compressed air to a plurality of said cylinders simultaneously according to the position at the 20 moment of the pistons in the respective cylinders.

22. The invention as defined in claim 21, in which each rocker has two cam followers, one to engage and be engaged by the cam when the engine is started forwardly and the other to engage and be engaged by the cam when the engine 25 is started in reverse direction.

23. The invention as defined in claim 21, in which some of the cams are shorter than others, and in which the rockers engage only the longer 30 cams so that compressed air is admitted to only those cylinders whose associated cams are long, and in which there is means for injecting fuel for a regular firing charge in those cylinders in which compressed air has not been admitted. 35

24. The invention as defined in claim 21, in which each rocker has two cam followers, one to engage and be engaged by the cam when the engine is started forwardly and the other to engage and be engaged by the cam when the engine is started in reverse direction, in which some 40 of the cams are shorter than others, and in which the rockers engage only the longer cams so that compressed air is admitted to only those cylinders whose associated cams are long, and in which 45 there is means for injecting fuel for a regular firing charge in those cylinders in which compressed air has not been admitted.

25. In a Diesel-type engine having a plurality of cylinders, pistons, and means driven by the pistons, means for starting the engine by compressed air including a plurality of valves each 50 individual to one cylinder, and a plurality of cams each individual to a cylinder and controlled as to position by the position of the piston in its 55 associated cylinder, and suitable means for making said cams operable to open a plurality of said valves to admit compressed air to a plurality of said cylinders simultaneously according to the position at the moment of the piston in the respective cylinders. 60

26. The invention as defined in claim 25, in which the last-named means is shiftable to open certain of said valves when the engine is to be started forwardly, and others of said valves when the engine is to be started in reverse direction. 65

27. The engine as defined in claim 25, in which only certain of said valves are opened to admit compressed air to the cylinders, and in which there is means for injecting fuel for a regular firing charge in those cylinders in which compressed air has not been admitted. 70
